UNITED STATES PATENT OFFICE.

HARRY O. BARTLETT, OF WASHINGTON, DISTRICT OF COLUMBIA, ASSIGNOR TO BOWERS & BARTLETT, INC., OF WASHINGTON, DISTRICT OF COLUMBIA, A CORPORATION OF MARYLAND.

DESIGN FOR A FRAME FOR A CLOTHES-WRINGER.

58,010.

Specification for Design.

Patented May 31, 1921.

Application filed August 16, 1920. Serial No. 403,961. Term of patent 14 years.

To all whom it may concern:

Be it known that I, HARRY O. BARTLETT, a citizen of the United States, residing at Washington, in the District of Columbia, have invented a new, original, and ornamental Design for a Frame for a Clothes-Wringer, of which the following is a specification, reference being had to the accompanying drawings, forming a part thereof.

The figure is a perspective view of a frame for a clothes wringer embodying my invention.

I claim:

The ornamental design for a frame for a clothes wringer, as shown.

HARRY O. BARTLETT.
